(73) Assignee: **NEC Corporation**, Tokyo (JP)

Primary Examiner—Kay H. Chin
(74) Attorney, Agent, or Firm—Sughrue Mion, PLLC

(**) Term: **14 Years**

(57) **CLAIM**

(21) Appl. No.: **29/151,156**

The ornamental design for an operation machine for a portable wireless terminal equipment, as shown.

(22) Filed: **Dec. 5, 2001**

DESCRIPTION

(30) **Foreign Application Priority Data**

Jun. 6, 2001 (JP) 2001-016544

(51) **LOC (7) Cl.** **14-02**

(52) **U.S. Cl.** **D14/411; D19/36**

(58) **Field of Search** D14/411; D19/53-58,
D19/81-85, 35-36, 41-51; 401/34, 52,
195, 202, 98, 209, 262; 178/19.01-19.05;
345/179-183

(56) **References Cited**

FIG. 1 is a perspective view of the top, bottom and right side of an operation machine for a portable wireless terminal equipment showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
